UNITED STATES PATENT OFFICE.

JOHN ASPENLEITER AND OTTO A. MILLER, OF CINCINNATI, OHIO.

TOILET-PAPER HOLDER.

No. 922,745.

Specification of Letters Patent.

Patented May 25, 1909.

Application filed November 23, 1908. Serial No. 464,065.

To all whom it may concern:

Be it known that we, JOHN ASPENLEITER and OTTO A. MILLER, citizens of the United States, residing at Cincinnati, in the county 5 of Hamilton and State of Ohio, have invented certain new and useful Improvements in Toilet-Paper Holders, of which the following is a specification.

Our invention relates to improvements in 10 toilet paper holders.

One of its objects is to provide a holder which is capable of being constructed entirely of sheet metal stampings.

Another object is to provide a holder 15 adapted to support a variety of rolls of paper of different dimensions.

Another object is to provide improved means for adjusting the tension on the rolls.

Another object is to provide a holder from 20 which the roll cannot be stolen or removed before it has been unwound.

It further consists in certain details of form, combination and arrangement, all of 25 which will be more fully set forth in the description of the accompanying drawings, in which,

Figure 1 is a side elevation of our improved holder. Fig. 2 is a front elevation of the same. Fig. 3 is a section on line x—x of Fig. 30 1. Fig. 4 is a perspective view of the locking bar. Fig. 5 is a side elevation of a movable bracket detached and illustrating a modified form.

In the accompanying drawings, A, represents the base plate which is attached to the 35 wall and carries the roll supporting parts.

B, represents a bracket member rigidly attached to the base, A. The bracket, B, is provided with curved projections, b, b', 40 which project into the central opening in the roll of toilet paper and serve as a journal for one end of the roll.

C represents a locking bar which is preferably rigidly attached to bracket, B, and projects therefrom between the members, b, b'. The bar, C, is forked, and its free ends, c, c', 45 provided on their outer edges with teeth, c², the teeth of the respective ends, c, c', being preferably staggered instead of arranged in 50 pairs.

D represents a movable bracket member which is provided with inwardly projecting members, d, d', similar to members, b, b', to serve as a journal for the opposite end of the

roll. The free ends of members, d, d', are 55 provided with inwardly turned projections, d², d³, to engage the teeth, c², of bar, C.

As shown in Figs. 1, 2 and 3, the bracket, D, has a foot piece, D', which slides to and from bracket, B, in ways on the base, A, said 60 ways being preferably formed by stamping up lugs or projections, a, a', from base, A. The free ends of brackets, B, D, are preferably provided with outwardly curved heads, 65 or fenders, E.

In the modification, Fig. 5, the movable bracket member, F, has a foot, F', hinged thereto at, f, by means of ears formed respectively on the members, F, F', thus permitting the bracket, F, to turn on pivot, f, as 70 well as to slide relative to the base.

In practice the member, D, is detached, or, the member, F, may be detached, or turned over out of the way. The roll of toilet paper is then slipped over the bar, C, with 75 one end pivoted on the projections, b, b'. The bracket, D, is then engaged with the ways of the base and pressed against the opposite end of the roll with the projections, d, d', forming a pivotal support for the roll. 80 The forked ends of the bar, C, spring toward each other to enter between the projections, d, d', and the teeth, c² engage the projections, d², d³, to prevent the parts being separated until the roll of paper has been unwound, 85 when the forked ends can be pressed together between the fingers of the operator to release the bracket, D. By adjusting the pressure of the brackets, B, D, against the ends of the roll, the tension required to unroll the paper 90 can be increased to the desired extent, and by staggering the teeth, c², of bar, C, as indicated in Fig. 2, so that the teeth of the respective arms, c, c', successively engage alternately the projections, d², d³, a fine adjustment of the tension on the roll is attained. 95 Where the form of bracket, Fig. 5 is employed, it is only necessary to slidably adjust the bracket relative to the base to meet the requirements of a new roll of different proportions. The plate, D', serves to cover the heads of the screws, K, K', by means of 100 which the plate, A, is attached to the wall, thus preventing the screws being removed by vandals.

The mechanism herein illustrated and described is capable of being formed entirely from stampings, and may thus be produced 105

at small expense and at the same time so as to be capable of plating or fine finish, to match the grade of work desired.

The mechanism herein illustrated and described is capable of considerable modification, without departing from the principle of our invention.

Having described our invention, what we claim is:

- 10 1. In an article of the character indicated a base, a stationary bracket adapted to pivotally support one end of a roll of paper, a toothed locking bar carried rigidly by said stationary bracket, a bracket adapted to pivotally support the opposite end of a roll of paper and to engage the teeth of said locking bar, said last named bracket being movable to and from said stationary bracket and adjustably supported relative to said base.
- 20 2. In an article of the character indicated, a base, a stationary bracket adapted to pivotally support one end of a roll of paper, a forked locking bar carried by said bracket and provided at the outer edges of its free end with teeth, a bracket member adapted to pivotally support the opposite end of a roll of paper, and provided with projections to engage the teeth of said locking bar, said last named bracket being movable to and from said stationary bracket and adjustably supported relative to said base.
- 30 3. In an article of the character indicated, a base, a stationary bracket adapted to pivotally support one end of a roll of paper, a second bracket adjustably supported relative to said base so as to move to and from said stationary bracket, and adapted to pivotally support the opposite end of a roll of paper, and a forked toothed locking bar carried by one of said brackets and adapted to engage a projection on the opposite bracket.
- 40 4. In an article of the character indicated, a base, a pair of brackets supported upon said base and adjustable to and from each

other, and a forked locking bar carried by one of said brackets and whose free ends are toothed upon their outer edges and adapted to spring to and from each other to engage a projection on the other bracket.

5. In an article of the character indicated, 50 a base, a stationary bracket adapted to pivotally support one end of a roll of paper, a second bracket pivotally attached to a shoe, said shoe being adjustably mounted relative to said base and a locking bar having a series 55 of teeth adapted to successively engage a projection on the opposite bracket.

6. In an article of the character indicated, 60 a base, a stationary bracket adapted to pivotally support one end of a roll of paper, a second bracket adjustably supported relative to said base so as to move to and from said stationary bracket and adapted to pivotally support the opposite end of a roll of paper, and a forked locking bar carried by one of 65 said brackets, one fork having a series of teeth adapted to successively engage a projection on the opposite bracket, and the opposite fork serving to hold said teeth in engagement.

7. In an article of the character indicated, 70 a base, a pair of brackets supported upon said base and adjustable to and from each other, and each adapted to support an end of a roll of paper, and a forked locking bar carried by one of said brackets having a series 75 of teeth on one fork adapted to successively engage a projection on the opposite bracket, the opposite fork serving to hold said teeth in engagement.

In testimony whereof we have affixed our signatures in presence of two witnesses.

JOHN ASPENLEITER.
OTTO A. MILLER
